UNITED STATES PATENT OFFICE.

PATRICK J. MADDEN, OF CHICAGO, ILLINOIS.

DESIGN FOR A DRINKING-FOUNTAIN.

42,364.

Specification for Design.

Patented Mar. 26, 1912.

Application filed January 5, 1912. Serial No. 669,710. Term of patent 14 years.

To all whom it may concern:

Be it known that I, PATRICK J. MADDEN, a citizen of the United States, residing at Chicago, in the county of Cook and State of Illinois, have invented a new, original, and ornamental Design for Drinking-Fountains, of which the following is a specification, reference being had to the accompanying drawing, which forms a part thereof, and in which—

Figures 1, 2, 3 and 4 are respectively a side elevation, a front elevation, a rear elevation and a plan view of a drinking fountain embodying the new design.

I claim:

The ornamental design for a drinking fountain, as shown.

PATRICK J. MADDEN.

Witnesses:

JOHN JOHNSTONE,

HENRY W. LEWIS.
